UNITED STATES PATENT OFFICE.

JOHN WILSON BROWN, JR., OF PHILADELPHIA, PENNSYLVANIA, ASSIGNOR
TO THE ENTERPRISE MANUFACTURING COMPANY OF PENNSYLVANIA,
OF SAME PLACE.

REGISTERING-PUMP.

SPECIFICATION forming part of Letters Patent No. 665,390, dated January 1, 1901.

Application filed August 5, 1897. Serial No. 647,218. (No model.)

To all whom it may concern:

Be it known that I, JOHN WILSON BROWN, Jr., a citizen of the United States, residing in Philadelphia, Pennsylvania, have invented
5 certain Improvements in Registering-Pumps, of which the following is a specification.

The main object of my invention is to construct a measuring-pump that will accurately measure the liquid pumped and which need
10 not be primed.

A further object of the invention is to provide a pump that can be accurately and cheaply manufactured and which can be readily taken apart for cleansing or for repairs;
15 and a still further object of the invention is to so construct the pump that it can be inserted into a comparatively small opening in the barrel.

My invention is especially adapted for use
20 in pumping molasses and syrups and like liquids from barrels, and it is a substitute for the measuring-faucet commonly used for this purpose.

In the accompanying drawings, Figure 1 is
25 a view of my improved molasses-pump. Fig. 2 is an enlarged sectional view of the upper end of the pump. Fig. 3 is a sectional plan view on the line 3 3, Fig. 2. Fig. 4 is a vertical sectional view of the lower portion of
30 the pump on the line 4 4, Fig. 6. Fig. 5 is a vertical sectional view on the line 5 5, Fig. 6. Fig. 6 is a sectional view on the line 6 6, Fig. 4; and Fig. 7 is a sectional view on the line 7 7, Fig. 4.

35 The pump is made in three sections—namely, a stem A, a head A', and a pump-casing B. The head A' is secured to the upper end of the stem A and has a tubular extension A², forming the outlet-nozzle of the pump. The head also carries the driving mechanism, as well as the registering mechanism, of the pump. The pump-casing B is attached to the lower end of the tube A and contains the pumping mechanism proper, which is connected to the driving mechanism through a rod extending through the tube A. I make the outside of the pump-casing B concentric with the tubular stem A, so that I am enabled to reduce the amount of work necessary in manufacturing the pump and make
45
50

it neat in appearance. Also by having the parts concentric the diameter of the hole through which the pump must pass into the barrel can be just the size of the casing, and the pump can be readily inserted into or removed from the barrel.
55

On the stem A of the pump is clamped a sleeve C, having flanges c, which are preferably secured to the upper head of the barrel, so as to prevent the pump moving when once placed in position. On the lower portion of the pump-casing B are spurs c', which rest on the interior surface of the bottom edge of the barrel, so that when the sleeve C and the spurs are fixed the pump is perfectly rigid.
65

The upper end of the stem A is screw-threaded in the present instance, and the head A' is screwed upon this end of the stem, and there is a passage in the head communicating with the passage in the outlet extension A². At the end of this extension is a valve-chamber a, having a valve-seat at the nozzle, and in the chamber is a valve E for cutting off the flow of molasses from the pump in order to prevent dripping after the receptacle
70 is filled with the required amount of molasses. This valve is flush with the mouth of the nozzle when it is closed, so that there are no exposed cavities at the outlet of the pump for the accumulation of the molasses,
75 which would attract flies and other insects. By making the valve flush, as shown in Fig. 2, both the bottom of the valve and the nozzle can be wiped clean. The valve in the present instance has an inclined slot e, in
80 which rests a pin e', projecting from the casing. The valve is provided with a suitable handle e², so that on turning the handle the valve can be raised or lowered.
85

Projecting from the head A' is a stud a',
90 and on this stud is a bevel gear-wheel D, having a handle d, by which it is turned. This bevel gear-wheel meshes with the bevel-pinion D', having its lower bearing in the head A' and its upper bearing in the present instance in a plate F, mounted in a case A³, which in this instance contains the registering mechanism. The axis of this pinion D'
95 is coincident with that of the tube A, and the lower bearing is provided with a suitable
100

packing or stuffing box d' . This stuffing-box prevents the leakage of molasses or other fluid pumped through the bearing.

Within the casing B is a pump-chamber B' , and mounted in this chamber is the hub H of the pumping mechanism. This hub is eccentrically situated within the casing, and in the upper end of the hub is a socket h , and in the lower end of the bevel-pinion D' is a socket. Extending from the pinion to the hub is a shaft G . This shaft in the present instance is square, and the sockets in the hub and in the pinion are shaped to conform to the shaft, and as the axis of the pinion is coincident with the axis of the tube A and the hub is eccentric thereto the shaft G will be inclined or diagonal with respect to the axis of the tube. The connections are comparatively loose, so that the eccentrically-situated hub can be readily driven from the concentric bevel-pinion. Furthermore, the shaft is not attached to either the bevel-pinion or the hub, so that when it is desired to remove the pinion or the hub either one can be removed by simply withdrawing it from the shaft.

Sliding in the hub H are two blades $h' h^2$, fitting the cam-shaped chamber B' of the pump-chamber, governing the sliding movement of the blades in the hub. The blades are cut away at the center to allow them to pass each other and to slide. Other common forms of blades may be used without departing from my invention. The hub in the present instance rests upon a plate B^2 and has its lower bearing in said plate, the upper bearing of the hub being in the casing.

B^3 is the cap-section, which is screwed into the end of the casing B and holds the plate B^2 in position against the casing. The inlet-port b is formed in the plate B^2 and also in the cap-section B^3 , as indicated in Fig. 5. The inlet-port communicates with the chamber B at one side, while the outlet-port b^2 , formed in the casing, communicates with the upper portion of the chamber at the opposite side. The cap-section B^3 in the present instance has feet provided with spurs, which are forced into the bottom of the barrel, so as to rigidly hold the lower portion of the pump, raising the cap sufficiently off the bottom to allow the molasses to enter the inlet-opening. I prefer to screen the inlet-opening, so as to strain the molasses as it enters the pump, preventing sticks and other foreign matter entering the chamber and clogging the pump and barrel. J is a screen within the cap-section B^3 for this purpose.

Above the pumping-chamber B' in the present instance is the valve-chamber, in which is a valve-plate I' . In this valve-plate are one or more seats i —two in the present instance—for the valves II . The seats are tapered, and the valves are tapered to correspond to the seats and have stems which are guided by spiders carried by the plate, so that as the hub is turned the molasses will be forced up through the outlet-passage b^2 into the valve-

chamber and will pass the valves and enter the tube A .

The valve-plate I is supported by the casing B and is held in place by a reducing-sleeve B^4 , which is threaded and is screwed into the casing B , and the lower portion of the stem A is also threaded and screwed into the threaded portion of the reducing-sleeve. It will be understood, however, that in some instances this reducing-sleeve may be dispensed with and the stem A screwed directly into the casing.

I will now describe the mechanism for registering the amount of molasses passing through the pump.

The bevel-pinion D' , which is mounted in the head of the pump, has an eccentric-pin d^2 , on which is mounted a planet gear-wheel F' . This wheel has two sets of gear-teeth $f f'$, and the two portions of the wheel are of different diameters. The teeth f mesh with teeth f^2 on the fixed plate F , and the teeth f' mesh with the internal teeth f^3 on the wheel F^2 , connected with the dial-hand F^3 , so that the dial-hand will only move a very short distance for each revolution of the bevel-wheel D . In the present instance the dial-hand moves one sixty-fourth of a turn to one turn of the pump. The arrangement of the teeth and the relative diameters of the wheels will depend upon the quantities indicated upon the dial and the capacity of the pump to lift a certain amount of molasses at each revolution.

It will be seen that the pump is so constructed that when it is wished to remove the pumping-hub from the casing the cap and plate at the lower end of the pump can be detached and the hub withdrawn, as it is not secured to the shaft, but simply loosely coupled to it. The same is the case with the driving-pinion D' , mounted in the head of the pump, and this can be readily removed by detaching the plate F . Moreover, the shaft being detachably connected to the hub and removable through the bottom of the tube said shaft can be readily removed without disturbing or necessitating the removal of the driving pinion or wheel D' or the packing.

The operation of the pump is as follows: On turning the handled bevel gear-wheel D the hub H and its blades are turned within the chamber B' , and a given quantity of molasses will be forced up into the passage a^2 in the stem and into the extension A^2 . The valve E being lifted, an amount of molasses will be forced out of the nozzle equivalent to the amount pumped, and simultaneously with this action of the pump the registering mechanism will register the proper amount passing through the pump—in other words, the amount discharged from the pump.

By numerous experiments I have found that I can accurately register by the apparatus shown and described the amount discharged by the pump, and I can so regulate the gearing that a certain number of turns

will be equivalent to a pint of molasses discharged, and this number multiplied will give the quarts and gallons, so that it will be seen that a retail grocer, for whose use this 5 pump is mainly intended, can readily measure into any suitable vessel any quantity of molasses without having to first prime the pump or to provide a suitable measuring vessel to receive the molasses from the pump.

10 By arranging the pumping elements at the lower end of the stem I dispense with the need of priming the stem of the pump, and by locating the measuring elements at the upper end I keep them clear of the molasses, preventing clogging and insuring accurate measurement.

I claim as my invention—

15 1. The combination in a pump, of a tubular stem, a pump-casing at the lower end of the stem and concentric therewith, an inlet for the casing, a hub mounted eccentrically in the said casing and having one or more blades, a driving means at the upper end of the tube and concentric therewith, and a diagonal shaft connecting the concentric driving means and the eccentric pump-hub, substantially as described.

20 2. The combination in a pump, of a tubular stem having a casting at each end, the casting at the upper end having the outlet-passage and carrying the driving means for the pump, the casting at the lower end of the tube forming the pump-chamber and arranged concentric with the tube and having an inlet-opening, an eccentrically-arranged pumping-hub, and a diagonal shaft connecting the driving means and the pump-hub, substantially as described.

25 3. The combination in a pump, of a tubular stem, a casting at the upper end of said stem having an outlet-opening and carrying a driving-hub concentric with the stem, a pump-casing at the lower end of the stem concentric with the stem, a pump-hub eccentrically mounted in the casing, the driving-hub and the pump-hub having sockets and a connecting-rod mounted in the sockets, whereby the pump-hub is driven through the rod, substantially as described.

30 4. The combination of a tube, a pump-casing secured to the tube, and having a pump-chamber, a hub eccentrically mounted in said chamber and having blades, a bearing-plate supporting the hub, a driving means at the upper end of the tube and concentric therewith, a diagonal shaft connecting said driving means with the eccentric hub, an inlet-passage communicating with the pump-chamber at one side of the hub, and an outlet-passage communicating with the chamber at the opposite side of the hub, said outlet-passage communicating with the tube, a discharge-opening at the opposite end of the tube, substantially as described.

35 5. The combination in a pump, of a tubular stem, a concentric pump-casing secured to the lower end of the stem and inlet and out-

let openings therein, a hub mounted eccentrically in the said casing, a concentric driving means at the upper end of the tube, and 70 a diagonally-arranged connecting-shaft connecting the concentric driving means with the eccentric pump-hub, and an outlet at or near the upper end of the tube.

6. The combination in a pump, of a tubular 75 stem, a concentric pump-casing made in a single casting having a chamber and a passage cored therein forming a communication between the chamber and the stem, a hub eccentrically mounted in the chamber of the 80 casing and having its upper bearing in the casting, an inlet-opening communicating with the chamber, a detachable cap secured to the bottom of the casing and holding the hub in position, and means for turning said hub, 85 substantially as described.

7. The combination of a cylindrical tube, a pump-casing whose axis is coincident to that of the tube, said casing having a pump-chamber, a hub mounted eccentrically in the chamber, blades carried by said hub, an inlet to the casing, an outlet from the casing communicating with the tube, with a head secured to the upper end of the tube and having an outlet-spout, a driving-wheel mounted in the 95 said head, said driving-wheel having its axis coincident with that of the tube, and a diagonal shaft coupled to the said concentric driving-wheel and to the eccentrically-located hub, substantially as described.

100 8. The combination, in a registering-pump, of a tube, a pump-cylinder secured to the bottom of the tube, a head secured to the upper end of the tube, a stuffing-box in said head, a gear-wheel having a long hub, said hub being mounted in the stuffing-box, a shaft detachably connected with said hub and removable through the bottom of the tube and connecting the wheel to the pumping mechanism, whereby the shaft may be removed 105 without removing the wheel or packing, and means for driving the said wheel, substantially as described.

110 9. The combination, in a registering-pump, of a tube, a pump-cylinder secured to the 115 bottom of the tube, pumping mechanism within said cylinder, a head, an outlet-opening therein, said head having an extension above the outlet-opening, a bevel-gear above the said extension and having a long hub mounted therein, a packing in the extension around the long hub, a shaft detachably connected with the hub and removable through the bottom of the tube and connecting said bevel-gear to the pumping mechanism, whereby 120 said shaft may be removed without removing the wheel or packing, and means for driving said wheel, substantially as described.

125 10. The combination in a pump, of a tubular stem, a head secured to the upper end of the 130 tubular stem, an outlet-passage in said head, a driving-wheel having its axis coincident with that of the stem, said wheel having its bearing in the casing and detachable from the

end thereof, a pump-casing secured to the opposite end of the stem, a pumping-hub removable from the end of the pump-casing, a shaft so coupled to the driving-wheel and the hub that either the hub can be removed from the casing, or the wheel from its bearing without removing the shaft, substantially as described.

11. The combination in a molasses-pump, 10 of the tube, a head secured to the tube having a hollow arm forming the spout, a valve at the end of the spout, a driven wheel mounted in the head, registering mechanism geared to the said driven wheel, a pump-casing secured to the lower end of the tube, a hub adapted to the casing, blades in said hub, a shaft connected to the hub and to the driven wheel, a stud projecting from the head, and a driving-wheel mounted on the stud and 20 gearing with the driven wheel, substantially as described.

12. The combination in a molasses-pump, 15 of the stem, a pump-casing at the lower end of the stem and having an inlet-opening for the molasses, a rotary pumping device within the casing and having its hub arranged at one side of the center, a shaft coupled to the rotary pumping device, a bevel-pinion coupled to the opposite end of the shaft, said pinion 25 having an extension, registering mechanism carried thereby, and a driving bevel-wheel geared to the pinion so that on rotating the bevel-wheel the pumping mechanism and registering mechanism will be rotated, substantially as described.

13. The combination in a molasses-pump, 30 of the stem, a pump-casing at the lower end of the stem and having an inlet-opening for the molasses, a rotary pumping device within the casing and having its hub arranged at one 35 side of the center, a check-valve, a shaft

coupled to the rotary pumping device, a bevel-pinion coupled to the opposite end of the shaft, a stuffing-box in the upper end of the casing to which the pinion is adapted, with a driving bevel-wheel meshing with the pinion, said pinion having an extension, one portion of the extension being set to one side of the center, registering mechanism carried thereby, substantially as described.

14. The combination in a registering molasses-pump, of the stem, the pump-casing at the lower end, pumping mechanism therein, a nozzle at the upper end, a pinion, means for turning the pinion, a shaft connecting the pinion with the pumping mechanism, an eccentric-pin extending from the pinion, a planet gear-wheel mounted on the eccentric-pin, and having two sets of teeth, one set of teeth meshing with teeth on a fixed plate, the other set of teeth meshing with teeth on a movable plate, and a hand connected with the movable plate so that on turning the pumping mechanism the hand will register the amount of liquid passing through the pump, substantially as described.

15. The head of a pump made in a single casting, consisting of a vertical tubular section, with a hollow arm projecting from one side thereof, a stud projecting from the other side and a cup on the end of the vertical tubular portion adapted to inclose the registering mechanism of the pump, substantially as described.

In testimony whereof I have signed my name to this specification in the presence of two subscribing witnesses.
